[54] BOWLING LANE DIVISION CAPPING

5,358,448 10/1994 Stephens 473/113
5,800,274 9/1998 Widrick et al. 473/113

[75] Inventor: Troy A. Recknagel, Muskegon, Mich.

Primary Examiner—Prabhakar G. Deshmukh
Attorney, Agent, or Firm—Price, Heneveld, Cooper, DeWitt
and Litton[73] Assignee: Brunswick Bowling & Billiards
Corporation, Muskegon, Mich.

[**] Term: 14 Years

[57] CLAIM

[21] Appl. No.: 29/081,695

The ornamental design for bowling lane division capping, as
shown and described.

[22] Filed: Jan. 8, 1998

DESCRIPTION

[51] LOC (6) Cl. 21-02

FIG. 1 is a fragmentary top and left side perspective view of
a bowling lane divider cap showing my new design; the top
and right side perspective view being a mirror image
thereof;

[52] U.S. Cl. D21/785

FIG. 2 is a top plan view thereof;
FIG. 3 is a left side elevational view thereof; the right side
elevational view being a mirror image thereof;
FIG. 4 is a front elevational view thereof; the rear eleva-
tional view being a mirror image thereof; and,[58] Field of Search D21/785, 786;
473/108-117, 54; D25/122, 121, 123, 124,
125FIG. 5 is a bottom plan view thereof.
FIGS. 1 and 3 are drawn in smaller scale. It is understood
that the invention shown in FIGS. 2, 3 and 5 indicates
indefinite length.
